DAM

Filed Sept. 17, 1927

INVENTOR
Fred A. Noetzli

UNITED STATES PATENT OFFICE

FRED A. NOETZLI, OF LOS ANGELES, CALIFORNIA

DAM

Application filed September 17, 1927. Serial No. 220,197.

This invention relates to the construction of concrete and masonry dams and the primary object of the invention is to provide a dam of this type which will be safer and less expensive and which can be built in a shorter period of time than dams such as heretofore constructed.

Most concrete and masonry dams as heretofore constructed have been of the gravity, arch, multiple arch or deck slab type. Some of these dams depend for stability upon the weight of the structure alone, such as gravity dams. Others, like arch and multiple arch dams, depend upon arch action, and in deck slab dams the water pressure is supported by slab or beam action.

In multiple arch and deck slab dams the water pressure is transmitted by means of arches or deck slabs upon buttresses. This transmission of stresses involves arch action or bending moments which may introduce large stresses in the deck and necessitates, in some cases, the use of reinforcing steel for taking care of tension stresses. The decks of these dams are usually thin and are subject to deterioration from frost action.

In many buttressed dams as built heretofore, including multiple arch dams, there have developed in the buttresses cracks due to shrinkage and temperature deformations, and also due to load conditions.

The objects of my invention are, first, to build a dam comprising buttresses provided with joints tending to facilitate expansion and contraction of the buttresses; second, to build such a dam of buttresses having enlarged buttress heads for resisting the water pressure, and also to build such a dam of buttresses supporting an arched deck, and having joints in the buttress heads and in the arches tending to facilitate expansion and contraction of these members.

Other objects of my invention will be disclosed in the following detailed description.

In the accompanying drawings, forming a part of this specification,

Figure 1 is a schematical elevation of the improved dam, looking up-stream.

Figure 2 is a typical side elevation of one

buttress and buttress head, as seen from the line 2—2 of Figure 1.

Figure 3 is a horizontal section on the line 3—3 of Figure 2.

Figure 4 is a section on the line 4—4 of Figure 1.

Figure 5 is a horizontal section on the line 5—5 of Figure 4.

Referring to Figure 1. The dam shown comprises buttresses B, some of the buttresses having an enlarged buttress head 6 toward the up-stream side of the buttress wall 7, and others having arches A. The dam shown in Figure 1 has buttresses with buttress heads in the deeper part of the canyon across which the dam is built, and it has other buttresses with arches, at both wings of the dam where the height of dam is smaller than in the center. It is to be understood, however, that I may build my improved dam of buttresses either with buttress heads or with arches, or with any other combination, including wings of gravity section or earth-fill, as the geology of the dam site and economic considerations may make it appear to be best suited.

Figure 2 is a side elevation of a buttress of my improved dam and shows joints 8 and 9, and joints 10, in the buttress wall, and in the buttress head, respectively. The joint 8 starts at a point near the foundation and extends upward towards the up-stream side of the buttress. The theory of the principal stresses in buttresses of dams indicates that there are certain maximum principal stresses in the buttresses of a dam which for a full reservoir are substantially perpendicular to the up-stream face and nearly parallel to the downstream face. (See Wegmann, "The Design and Construction of Dams," 8th edition, Part IV, "A mathematical discussion and description of multiple arch dams," by the writer.) Certain minimum principal stresses for the same load conditions are at all points perpendicular to the direction of the corresponding maximum principal stresses. I have found in investigating many of the existing buttressed dams that the minimum principal stresses for a full reservoir are often in excess of 100 pounds per square inch tension and may therefore have been at least 100

partly responsible for the cracks in some of these dams. In other buttressed dams cracks have formed already during construction, giving evidence of internal temperature and shrinkage stresses. Such shrinkage cracks have occurred in spite of strong steel reinforcement in the buttresses, and some of these cracks are of irregular zig-zag shape and occur in planes of high shear, thus endangering seriously the stability of the buttresses.

One of the objects of my invention is to localize the shrinkage cracks by providing special expansion joints 8 and 9 as shown on Figure 2. These joints are arranged in such a way that the minimum principal stresses in the buttress with reservoir full are at all elevations substantially perpendicular to the joints, and if these minimum principal stresses should be tensioned they would merely tend to open the joints. This would not affect the stability of the dam materially because there would be little, if any, shear, in the plane of the joints, and the tension across the joint would be relieved.

The lines of the maximum principal stress are generally at a flatter slope than the downstream face of the buttress. Consequently the joints 8 and 9 will generally be at a greater distance from the down-stream face of the buttress at upper elevations than at lower elevations. The angle α' in Figure 2 is therefore generally smaller than the angle α . There may be a plurality of joints 8 and 9 especially in the case of high dams.

Referring to Figure 3, the joint 8 is shown to extend through the entire thickness of the buttress wall. The joint 8 is preferably provided with a key off-set K which should prevent the lateral movement of one part of the buttress wall relatively to the other part. I provide suitable means for preventing bonding of the concrete across the joint such as painting one side of the joint with coal tar, asphalt, or other material.

I may construct a joint extending only partly through the thickness of the wall as shown by joint 9 in Figure 3. A part of the thickness of the wall, in the present case, approximately the middle half, would then be solid and transmit a moderate amount of stresses. In case sufficient tension should occur, the joint would be likely to break also in the solid middle half of the buttress wall, the outer one quarter thicknesses providing a plane of minimum resistance. Consequently, in case the joint should open up it would be along pre-determined lines in the place where the designer should like to have it as it would do there the minimum damage. In order to facilitate construction, I may provide a thin sheet of tar paper, burlap, or other suitable material, extending entirely or part way through the thickness of the buttress and in the direction of the joint, and hold it proper-

ly in position, preferably by fastening it in advance of concreting to the outer forms and supporting it by wires or other suitable means. The concrete can then be placed as usual and can be readily made to flow around the sheet and on both sides of it.

I may place steel reinforcing bars 11 in the buttress wall to resist tension and shearing strains. I may either extend these bars across the plane of the joint, or I may stop some or all of the reinforcing bars on both sides of the joint. The bars 11 extending across the joint will not defeat the purpose of my invention, inasmuch as these bars will still permit of a slight opening and closing of the joint, but the bars will prevent excessive movement of the joint.

I may construct certain portions of my improved dam of buttresses with enlarged buttress heads, substantially as described in my application for Letters Patent, Serial No. 122,141, filed July 3, 1926. The up-stream face of the buttress head 6 has such a shape that the force of the water pressure is transmitted onto the buttress wall 7 through the buttress head in the same direction to that of the water pressure upon the up-stream face. I may provide the up-stream face of the buttress head 6 with a suitable waterproofing material W, such as asphalt, roofing paper, or the like, and protect the waterproofing and up-stream face with a concrete slab C of suitable thickness. Inasmuch as there may be water seeping through this slab, I may provide drainage canals D and drain holes, or other suitable means, for collecting and disposing of this seepage water.

Referring now to Figure 4, a section of my improved dam is shown on the line 4-4 of Figure 1.

Figure 5 shows a section on the line 5-5 of Figure 4. I may construct some of the buttresses of my improved dam with arches A springing from the up-stream face of the buttress. In order to increase the theoretical rise of these arches and increase thereby their flexibility, thus decreasing the temperatures stresses in the arches, I provide a joint 12 between the arches, this joint being located substantially on the center line of the buttress B. The joint 12 may be formed by a sheet of roofing paper or other material, suitably held in place during the concreting of the arches. The joint may therefore be formed without the use of additional form work.

In many multiple arch dams constructed in the past the pressure of the arches upon the buttress walls is so large that inclined tension stresses occur in the portions of the buttress walls near the up-stream side, and for some distance toward the down-stream side of the buttress. I reduce the intensity of these inclined tension stresses, by reducing the bearing pressure of the arches upon

the buttress walls by increasing the thickness of the buttress wall toward the up-stream side. This thickening of the buttress wall is not necessary over the entire length of the 5 buttress, but a gradual increase in thickness from a point between the up-stream and down-stream sides of the buttress toward the up-stream side, is sufficient and most economical.

10 In constructing my improved dam I erect suitable forms for the buttress wall 7, and I also provide a thin sheet 13 of suitable material preferably held to the forms and held in place during concreting of the buttress 15 wall 7. The sheet 13 may be of roofing paper, burlap or other suitable material. It may extend partly or wholly through the thickness of the buttress wall 7, preferably at approximately a right angle to the forms, and 20 said sheet 13 will extend substantially in the direction of the joints 8 and 9, and extend from a point near the foundation of the buttress wall 7 upwards and towards the up-stream side of the buttress wall 7. Concrete 25 is then poured into the forms and on both sides of the sheet 13. This construction is preferably made in steps, corresponding to pourings of concrete of 4 to 8 feet of height.

I may also form the joint 8 in the manner 30 that I pour, first a portion of the buttress wall 7 which is upstream of the joint 8, then making suitable provision, by painting, or otherwise, for preventing the bonding of the concrete across the joint 8, or across certain 35 portions of the joint 8, and then pouring the portion of the buttress wall 7 which is downstream of the joint 8. The joint 8 is substantially parallel to the direction of the maximum principal stresses when the reservoir is 40 full. A point of the joint 8 near the up-stream side of the buttress wall 7 is therefore at a greater distance from the down-stream face of the buttress than a point of 45 the same joint 8 near the foundation of the buttress wall 7.

I construct certain portions of my improved dam by building a buttress wall 7 and an enlarged buttress head 6, certain parts 14 of which extend laterally beyond the buttress wall 7, and I place and hold properly in position during concreting a sheet 15 of suitable material in the buttress head 6, this sheet to extend substantially perpendicularly to the up-stream face of the buttress head 6, and 55 reaching from the up-stream face to the down-stream face of the parts 14 of the buttress head 6. The joint 10 which is formed by the placing of a sheet 15 in the part 14 of the buttress head will tend to facilitate an irregular expansion and contraction of the buttress head 6 and thus tend to eliminate the danger of cracks forming in the buttress head 6 in a vertical direction.

I claim:

65 1. In a dam forming a reservoir, a buttress

provided with an expansion joint extending from a point near the up-stream side to a point near the foundation of said buttress and being substantially parallel to the direction of certain maximum principal stresses 70 in said buttress, when the reservoir is full.

2. In a dam a buttress provided with an expansion joint extending from a point near the up-stream side to a point near the foundation of said buttress, said point near the up-stream side being at a greater distance from the down-stream face of said buttress than said point near the foundation. 75

3. In a dam a buttress provided with an expansion joint forming an angle with a horizontal plane, said angle being at practically all elevations smaller than the corresponding angle between the down-stream face of said buttress and the horizontal at the same elevations. 80

4. In a dam a buttress provided with a plurality of expansion joints extending from points near the up-stream side to points near the foundation of said buttress, said points near the up-stream side being at a greater distance from the down-stream face of said buttress than said points near the foundation. 90

5. In a dam forming a reservoir, a buttress with a plurality of joints extending from points near the up-stream face to points near the foundation of said buttress, said points being substantially parallel to the direction of certain principal stresses in said buttress when the reservoir is full. 95

6. In a concrete dam a buttress wall having an expansion joint, said joint extending through the total thickness of said wall, a key off-set in said joint tending to prevent the lateral movement of the parts of said buttress wall on either side of said joint. 100

7. In a dam, a buttress wall which is divided upon downwardly and rearwardly extending predetermined lines into sections, which sections are designed to function substantially independently of each other in sustaining their proportions of the loads when the dam is loaded. 110

8. In a dam, a buttress wall which is divided upon predetermined lines into sections, said lines being substantially parallel to the lines of maximum principal stresses in the wall when the dam is fully loaded. 115

9. In a dam, a buttress wall which is divided upon predetermined lines into sections, said lines being substantially normal to the minimum principal stresses in the wall when the dam is fully loaded. 120

10. In a dam, a buttress wall which is divided upon downwardly and rearwardly extending predetermined weakened lines into sections, which sections are designed to function independently of each other in sustaining their proportions of the loads when the dam is loaded, and means preventing lateral 125

displacement of said sections relatively to each other.

11. In a dam, a buttress wall having a downwardly and rearwardly extending joint arranged along a line parallel to certain maximum principal stresses in the wall when the dam is fully loaded, and reinforcing rods extending across the joint.

12. In a dam a buttress wall having a sheet of suitable material embedded in the wall and extending partially therethrough in a transverse direction, said sheet serving to divide the wall into sections connected together by a weakened and relatively thin web whereby the sections may function practically independently of each other in sustaining stresses.

13. In a dam a buttress wall having sheets of suitable material extending inwardly from opposite sides of the wall in opposition to each other but having their opposed edges in spaced relation, said sheets serving to divide the wall into sections connected together by a comparatively weak thin connecting web whereby the sections may function practically independently of each other in sustaining stresses.

14. In a dam, a buttress wall which is divided by expansion joints disposed along predetermined lines into sections, said joints extending downwardly and rearwardly substantially parallel to the direction of certain maximum principal stresses in the buttress wall when the dam is fully loaded, and reinforcing steel bars connecting said sections.

15. In a dam, a buttress wall which is divided upon predetermined lines into sections, said lines being substantially parallel to the lines of certain maximum principal stresses in the wall when the dam is fully loaded, and means for preventing other than relatively small movements of two adjoining sections with respect to each other.

16. In a dam, a wall extending substantially crosswise to the direction of the dam, said wall being divided by predetermined areas of weakened bond into portions, said areas extending crosswise to the direction of said wall and extending substantially parallel to lines of zero shear in the wall when the dam is fully loaded.

17. In a dam, a buttress wall divided by an inclined expansion joint into sections, said expansion joint being arranged approximately parallel to a plane of zero shear in the wall when the dam is fully loaded.

FRED A. NOETZLI.
